UNITED STATES PATENT OFFICE

CARL F. BLEDSOE, OF CHICAGO, ILLINOIS, ASSIGNOR TO OGLE CONSTRUCTION COMPANY,
A CORPORATION OF ILLINOIS

DISTRIBUTING CHUTE FOR COAL BINS

Application filed April 15, 1927. Serial No. 183,940.

This invention relates to a distributing chute for coal bins and the like. It is generally the practice to provide storage bins for coal at coaling points for locomotives. These bins are usually so constructed that when the delivery chute is opened the coal automatically falls by gravity. These bins are filled by allowing the coal to run down a filling chute. The larger particles of coal gather considerable momentum in traveling down the filling chute with the result that they will fall forwardly in the bin. The dust and smaller particles or tailings will slowly gravitate down the bottom of the filling chute with very little if any momentum with the result that such dust and finer particles or tailings will fall in substantially the same spot in the bin and finally accumulate on the rear part of the bottom. Consequently when coal is drawn off from a bin, the larger particles will first escape. Consequently some locomotives will get all the larger particles of coal. Finally when the tailings are reached, it will be found that other locomotives get nothing but tailings which will smother the fire and impede generation of steam. A great deal of time and consideration has been given to this problem without any heretofore practical solution. It is an object of this invention to solve the above discussed problem or difficulty by distributing the tailings in the coal bin so that there will be no accumulation thereof with the result that each locomotive will receive a proper mixture of lumps and tailings. In other words, this invention serves to distribute the tailings so that each discharge from the bin will contain its proportioned amount of tailings.

The invention comprises the novel structure and combination of parts hereinafter described and more particularly pointed out and defined in the appended claims.

In the accompanying drawings which illustrate a preferred embodiment of this invention and in which similar reference numerals refer to similar features in the different views.

On the drawings: Figure 1 is a side elevational view of a

coal storage bin involving this invention with one side omitted for better illustration.

Figure 2 is a fragmentary sectional view upon the line II—II of Figure 1 with the coal omitted.

Figure 3 is a fragmentary top plan view of the bin.

Figure 4 is a side elevational view of a slightly modified form of coal bin involving this invention with a side removed.

Figure 5 is a fragmentary top plan view of the bin shown in Figure 4 taken upon the line V—V of Figure 4.

Figure 6 is a side elevational view of a further modified form of coal bin with a side removed showing a further application of this invention.

As shown on the drawings:

In referring to the drawings, it will be noted that in Figures 1 to 3 there is illustrated a coal bin of the single discharge type. This coal bin consists of a front wall 1, a rear wall 2 and a bottom 3 which slopes downwardly from the rear wall to the front wall. A coal delivery chute 4 extends from the lower part of the front wall toward which the coal naturally gravitates. The upper part of the coal bin is provided with a filling chute 5 and a stop plate 6 spaced forwardly of the end of the filling chute. Such coal bins are usually constructed in elevated position for the purpose of coaling locomotives. When such a coal bin is filled, the larger particles generally acquire considerable momentum and travel in advance of the tailings which should be understood as including the dust and finer particles. Heretofore, the tailings would drop substantially in a vertical direction and collect on the inclined bottom while the heavier particles would drop forwardly as illustrated. Consequently, the tailings were not properly distributed with respect to the heavier particles. The first locomotives to coal would naturally get the heavier and larger particles as these would first gravitate through the discharge chute, with the result that nearly all of the tailings would be left behind to be later discharged in a mass to a locomotive. This has proved a serious objection and to avoid the same, I have pro-

vided a tailings distributer or conveyor which is so positioned as to receive the tailings as they drop into the bin and distribute the same through the mass of coal in the bin.

It is evident that the tailings distributer 5 may assume various forms. As a matter of illustration, I have shown a slightly curved plate or member 7 which is supported upon a rod 8 secured in the ends of the bin at a suitable point beneath the filling chute, and at 10 a suitable point rearwardly of the discharge mouth of the chute so that the plate member 7, which may be termed a distributer or distributing chute, may intercept the tailings falling into the bin. The lower portion of the tailings distributing chute 7 is supported by 15 a pair of braces 8 extending from the front wall of the bin. These braces are so designed that the lower end of the distributing chute 7 will lie at a suitable point between the walls 1 and 3 of the bin that support the coal in order to properly distribute the tailings through the coal. It will be noted that the distributing chute 7 is generally directed toward 20 the point of the discharge chute 4, in the bin, so that the tailing will fall upon the lump coal. In the present instance, the distributing chute 7 is illustrated as of substantially the same width as the discharge end of 25 the filling chute. The width, however, may be varied as desired.

In Figures 4 and 5, there is shown a double discharge coal bin having a central apex 9 in its bottom to provide slopes toward the two discharge chutes 10 in order that the coal 30 may naturally gravitate toward such chutes. In this structure, there are a pair of distributing chutes 7 arranged side by side but oppositely directed, the upper ends of which are supported upon rods 11 carried by the bin. These distributing chutes are supported at 35 their lower portions by braces 8 attached to the front and side walls 13 and 14 of the bin. The lower ends of these distributing chutes 40 7 are directed toward their respective discharge chutes 10 so as to distribute the tailings over the lump coal that is in position to be discharged.

In Figure 6, there is shown a coal bin having 45 three discharge chutes 15, 16 and 17. The bottom of this coal bin has two upwardly directed apices 19 to provide proper gravitating slopes for the coal in order that the coal may naturally gravitate toward the predetermined points defined by the discharge outlets or chutes 15, 16 and 17. This coal bin should contain a pair of distributing chutes 7 arranged as shown in Figure 4, and a distributing chute 7 as arranged in 50 Figure 1.

In Figures 4 and 6 the upper ends of the distributing chutes are properly positioned beneath the coal receiving chutes 5 and 20 to intercept the tailings which is sometimes 55 also termed slack coal.

The coal is usually carried to these storage bins by skip bucket conveyors, and as the coal is dumped upon the receiving chutes it will gravitate into the bins, the courser particles will travel in advance of the slack coal or tailings. The tailings will be intercepted by the distributing chutes and will gradually travel on the same. The lump coal falling upon the distributing chutes will roll down the same or over the sides thereof and carry 70 some of the tailings therewith. The tailings that gravitate to the end of the distributing chute will naturally drop intermediate the lump coal adjacent the discharge chute. Consequently there will always be a uniform mixture of lump coal and tailings discharged to each locomotive. It will be appreciated that these distributing chutes do not take up much space nor do they prevent the complete filling 75 of the bins, since the coal can fall over the ends and under the same.

I am aware that many changes may be made and numerous details of construction may be varied through a wide range without departing from the principles of this invention and I, therefore, do not purpose limiting the patent granted hereon, otherwise than necessitated by the prior art.

I claim as my invention:

1. In a coal bin having a filling chute, an inclined curved distributing chute extending from a point adjacent the filling chute to a point intermediate the coal supporting walls of said bin for receiving and distributing the tailings.

2. In a coal bin having a bottom provided with an upwardly extending apex for causing the coal to gravitate toward two predetermined points, a filling chute for said bin, a tailings receiver and distributer extending from a point adjacent said chute toward one predetermined point and a second tailings distributer extending from said chute toward said other predetermined point.

3. In a coal bin having a coal receiving chute and a coal discharging chute towards which the coal is adapted to gravitate, and a distributing chute extending in curved formation from a point beneath the receiving chute toward the discharge chute for mixing the lump coal and tailings.

4. The combination with a coal bin having a filling chute, of an inclined tailings distributing chute supported within said bin, below and in spaced relation to said filling chute for receiving and distributing the tailings descending from said filling chute.

5. In a coal bin having a sloping bottom for causing the coal to gravitate toward a predetermined point, a filling chute for said bin and an inclined tailings distributer supported in said bin below and in spaced relation to said filling chute and extending toward said predetermined point.

6. In a coal bin having a filling chute, a

sloping bottom portion terminating in a discharge opening, in combination with a tailings distributor supported in said bin below and in spaced relation to said filling chute and sloping toward said discharge opening for the purpose set forth.

5 In testimony whereof I have hereunto subscribed my name at Chicago, Cook County, Illinois.
